UNITED STATES PATENT OFFICE.

ERNEST SCHULZ, OF ROUNDROCK, TEXAS.

CONNECTING-ARCH FOR CULTIVATORS.

SPECIFICATION forming part of Letters Patent No. 767,251, dated August 9, 1904.

Application filed June 16, 1904. Serial No. 212,793. (No model.)

To all whom it may concern:

Be it known that I, ERNEST SCHULZ, a citizen of the United States, residing at Roundrock, in the county of Williamson and State of Texas, 5 have invented a new and useful Connecting-Arch for Cultivators, of which the following is a specification.

This invention relates to riding-cultivators of that class in which two separate cultivator 10 gangs or rigs are employed, as is usually the case in riding-cultivators. The invention has for its object to enable the said gangs or rigs to be efficiently and conveniently controlled by the operator, more especially with regard 15 to the spacing apart of said gangs, which by my invention is made entirely within the control of the operator.

Specifically, the invention consists in an improved so-called "arch" whereby the cultivator-gangs are connected, said arch consisting of separate members suitably connected with each other and with the cultivator-gangs and means whereby the lower ends of said members may be adjusted with relation to each 25 other for the purpose of effecting the desired relative adjustment of the cultivator-gangs.

With these and other ends in view which will readily appear as the invention is better understood the same consists in the improved 30 construction and novel arrangement and combination of parts, which will be hereinafter fully described, and particularly pointed out in the claims.

In the accompanying drawings, Figure 1 is 35 a rear elevation of an ordinary type of riding-cultivator, showing my invention connected therewith. Fig. 2 is a rear elevation, enlarged, of my improved cultivator-arch. Fig. 3 is a side elevation of the same. Fig. 4 is a perspective detail view of the adjusting and operating lever. Fig. 5 is a detail edge view of the latter.

Corresponding parts in the several figures are indicated by similar numerals of reference. 45 The improved cultivator-arch includes two side members 1 2, the lower ends of which together constitute an arch of the desired dimensions, while the upper ends of said side members are provided with reinforcing-flanges 3, the member 2 being, in addition, pro-

vided with a segment-rack 4. The upper ends of the members 1 2 are connected by means of a transverse bolt 5, and a connecting-link 6, which is pivotally connected with the member 1, has a bifurcated outer end for the reception 55 of the limb or member 2. Said bifurcated end of the link is provided with a transverse slot 7 for the reception of a pin 8, which extends through the member 2, thereby limiting the movement of the latter within the limits 60 of the ends of the slot 7.

9 designates an operating-lever which is provided with an approximately circular head 10, having a central opening for the connecting-bolt 5, upon which it is mounted pivotally between the members 1 and 2, constituting the arch. The head 10, the narrow portion of which is disposed adjacent to the lever 9, from which the thickness of the rim of said head increases in opposite directions, as clearly 70 shown in Fig. 4 of the drawings, thus forms what may be termed a "double" cam, the wide ends of which are separated by recesses 11 in opposite sides of the disk or head. The lever 9 is provided with a spring-actuated dog 12, engaging the rack-bar 4, whereby the said lever may be maintained securely at any desired adjustment.

The operating-rod 13 of the dog 12 is provided in its upper end with a handle 14, which 80 lies closely adjacent to the handle 15 of the lever 9, so that it may be readily grasped when the handle of the lever is grasped for the purpose of adjusting the same.

The lower ends of the members 1 and 2 have 85 been shown as being provided with hooks 16, whereby convenient connection may be made with staples or eyes 17, provided for their reception upon the cultivator-gangs.

The operation of this device will be readily 90 understood. When it has been mounted in position upon the cultivator, the driver may by manipulating the lever 9 adjust the wide portions of the cam-head between the members 1 and 2 either above or below the connecting-bolt 5. If the wide portion of the cam is placed between the side members 1 2 above the connecting-bolt, it is obvious that the lower ends of said members are forced 95 in the direction of each other, thus lessening 100

the distance between the rigs or gangs of the cultivator. When, on the other hand, the wide portion of the cam-head is placed between the members 1 and 2 below the connecting-bolt 5, the lower ends of said members will be spread apart, thus increasing the distance between the cultivator-gangs. The link connection 6 serves to maintain the relative position of the members 1 and 2 and to prevent displacement.

If for any reason it shall be desired to permit the gangs to have free play with relation to each other, the operating-lever may simply be turned upon its fulcrum until the recesses 11 are in alinement with the members 1 and 2, when the cam not being interposed to space them apart the lower ends of said members 1 and 2 are capable of free play with relation to each other.

The improved adjusting device, as will be seen from the foregoing description, is extremely simple in construction and may be produced at a moderate expense. It is readily applicable to any ordinary cultivator and will enable the operator to have complete control over the implement.

Having thus described the invention, what is claimed is—

1. A cultivator-arch including a pair of side members, a bolt connecting said side members near their upper ends, and a cam-disk mounted for rotation upon said bolt between the side members.

2. A cultivator-arch including a pair of side members, a bolt connecting said side members near their upper ends, a cam-disk mounted for rotation upon said bolt, a lever connected with the cam-disk, and means for maintaining the latter in adjusted position.

3. A cultivator-arch including a pair of side members having upward straight extensions, a bolt connecting the latter, a rack-segment

upon one of said extensions, a cam-disk mounted for rotation upon the bolt between the extensions of the arch members, and a lever connected with said disk and carrying a spring-actuated dog engaging the rack-segment.

4. A cultivator including a pair of side members having straight extensions, a link pivotally connected with one of said members and having a bifurcated end for the reception of the other member and a transverse slot in said bifurcated end, a pin extending through said slot and through the member engaging the bifurcated end of the link, a bolt connecting the upper ends of the side members, a cam-disk mounted for rotation upon said bolt between the side members, and means for securing said cam-disk in adjusted position.

5. A cultivator-arch including two members loosely connected together near their upper ends, a cam-disk mounted for rotation between the upper ends of said side members, and means for manipulating and for securing the cam-disk at various adjustments.

6. A cultivator-arch including a pair of side members loosely connected near their upper ends, a link forming an auxiliary connection for said side members, a cam-disk mounted for rotation between said side members near their upper ends, said disk having an operating-lever and cams increasing in width from said lever in the direction of the opposite edge of the disk, and recesses between the wide ends of said cam, and means for retaining said disk at various adjustments.

In testimony that I claim the foregoing as my own I have hereto affixed my signature in the presence of two witnesses.

ERNEST SCHULZ.
